ELECTRIC VAPORIZER

Hal F. Costello, Toledo, Ohio, assignor to Coswell Products, Inc., Toledo, Ohio

Filed Feb. 8, 1972, Ser. No. 224,650

Term of patent 14 years

Int. Cl. D23—99

U.S. Cl. D23—148

FIG. 1

FIG. 1 is a front perspective view of the electric vaporizer showing my new design;

FIG. 2 is a bottom plan view of the electric vaporizer on an enlarged scale; and

FIG. 3 is a rear end elevation of the electric vaporizer on an enlarged scale.

The side of the electric vaporizer opposite to that appearing on FIG. 1 is identical with such disclosure.

I claim:

The ornamental design for an electric vaporizer, as shown and described.
